PRESS

Richard M. Norman, Chicago, and Norman F. MacMillin, Winnetka, Ill., assignors to MacMillin Engineering Corporation, Chicago, Ill., a corporation of Illinois

Application January 10, 1948, Serial No. 143,652

Term of patent 14 years

(Cl. D63—1)

To all whom it may concern:

Be it known that we, Richard M. Norman and Norman F. MacMillin, citizens of the United States, residing respectively at Chicago, in the county of Cook and State of Illinois, and at Winnetka, in the county of Cook and State of Illinois, have invented a new, original, and ornamental Design for a Press, of which the following is a specification, reference being had to the accompanying drawing, forming a part thereof.

In the accompanying drawings,

Fig. 1 is a front perspective view of a press, showing our new design.

Fig. 2 is a rear perspective view of the press.

Fig. 3 is a transverse sectional view through the control column taken along line 3—3 of Fig. 2.

The dominant feature of the design disclosed resides in the vertical control column extending

between the upper and lower frame sections having the configuration shown.

We claim:

The ornamental design for a press, substantially as shown and described.

RICHARD M. NORMAN.
NORMAN F. MACMILLIN.
